H. W. NEAL.

AUTOMATIC AIR CIRCULATOR FOR HEATING FURNACES.

APPLICATION FILED DEC. 28, 1921.

1,426,900.

Patented Aug. 22, 1922.

INVENTOR,
Harry W. Neal,
BY Joseph A. Minton,
Attorney.

UNITED STATES PATENT OFFICE.

HARRY W. NEAL, OF INDIANAPOLIS, INDIANA, ASSIGNOR OF ONE-HALF TO HALL-NEAL FURNACE COMPANY, OF INDIANAPOLIS, INDIANA, A CORPORATION OF INDIANA.

AUTOMATIC AIR CIRCULATOR FOR HEATING FURNACES.

1,426,900.

Specification of Letters Patent. Patented Aug. 22, 1922.

Application filed December 28, 1921. Serial No. 525,277.

To all whom it may concern:

Be it known that I, HARRY W. NEAL, a citizen of the United States, residing at Indianapolis, in the county of Marion, and 5 State of Indiana, have invented new and useful Improvements in Automatic Air Circulators for Heating Furnaces, of which the following is a specification.

In heating buildings with hot-air delivered through registers and pipes from a furnace, it frequently occurs that the delivery is at a long distance from the furnace or is so located with relation to prevailing winds as not to discharge an adequate supply of hot-air. It also happens under these conditions that the flow of air will be sufficient after it has been started through the pipe.

The object of my invention is to provide 20 a portable means for creating a vacuum at the register end of hot-air pipes that are not supplying heat in proper quantities, in order to start the flow of air through said pipes or to continue said flow in such cases 25 where that is required.

I accomplish these objects and other minor ones which will hereinafter appear, by the mechanism illustrated in the accompanying drawing, in which—

30 Fig. 1, is a vertical section of a portion of a building showing a hot-air supply pipe and register, with my invention operatively installed on the register. Fig. 2, is a view in side elevation of my device. 35 Fig. 3, is an underside plan view of the device illustrated in Fig. 2. Fig. 4 is a view in side elevation, on a larger scale, of a form of thermostat useful in automatic operation of my improvement.

40 Referring to Fig. 1, 5 is the floor, 6 a wall, 7 a hot-air supply pipe, 8 a floor-box for the register, and 9 the register, all of any suitable and usual construction.

45 My invention comprises a sheet metal body-member 10, of truncated pyramidal form, of a size and shape in bottom outline to rest upon the top of the register, upon the frame portion surrounding the usual grille work. From the top of the member 50 10 is an extension with vertical walls 11, with suitable air-openings 12 formed therein for the free discharge of hot-air therethrough. The top of the extension 11 is closed by a plate 12' having a central re-

cess 13 with downwardly tapering walls 55 funnel-like in shape for the double purpose of acting as a deflector of the hot-air coming up through the register, and for discharging it through the openings 12; and also providing a suitable recess within 60 which an electric-motor 14 of any usual or preferred design is mounted and protected. At the bottom or apex end of the conical portion 13 is a suitable bearing for the motor shaft, which extends therethrough, 65 and on the extending end of said shaft is a cross-arm 15, and on each end of said arm, close to the walls 11, are the oblique fan-blades 16, the obvious purpose of which is to blow the hot-air out of the body 10 by 70 the rotation of the motor shaft, thereby creating a partial vacuum in said body 10, which in turn produces a suction and draft through the pipe 7 of hot-air from the furnace. This induced draft will continue as 75 long as the motor remains in operation. Frequently, after the pipe 7 has become heated and the flow of air has been started through it, the flow will continue without further requirement of rotating fan-blades, 80 in which event the device will be lifted off the register, and may be used elsewhere if needed.

85 However, should weather conditions make the continued use of my device desirable, it may be allowed to remain in operation, and to start its operation automatically when the temperature of the room drops below a predetermined minimum, and also to stop the motor and fan when a maximum room-temperature has been reached, I prefer to introduce a thermostat 18 in the electric circuit through which current is supplied when operating the motor. This is shown in a simple form in Fig. 4, where in a bar 17 of two unequally expanding metals are utilized in the wellknown way to make and break the circuit at terminals 19. The device may be provided with a screw-plug 20 to be screwed into an electric light-socket or a base-socket, where the latter is available. The device may be used with a wall radiator by suitably suspending it there.

105 It is obvious that the design and proportions of my invention here illustrated are capable of variation without departure from the spirit of the invention, and I

therefore do not desire to be unduly limited to the form here illustrated and described, nor any more than is required by the appended claims, and what I claim
5 is—

1. In a hot-air heating system, the combination with a hot-air supply pipe and register, of a portable hood to cover the register, said hood having a top outlet, a
10 horizontally rotating fan located at the outlet and having relatively small radial arms terminating with vertical end vanes to insure minimum obstruction to the passage of air, and a top above the hood outlet having a funnel shaped member extending between the blades of the fan and directing the discharge of air between the cap and the hood.
- 15

2. In a hot-air heating system, the combination with a hot-air supply pipe and register, of a portable hood to cover the register, said hood having a top outlet, a horizontally rotating fan located at the outlet and having relatively small radial arms terminating with vertical vanes to insure 25 minimum obstruction to the passage of air, a top above the hood outlet having a funnel shaped member extending between the blades of the fan and directing the discharge of air between the cap and the hood, 30 and a motor in the funnel shaped member drivingly connected with the fan.

Signed at Indianapolis, Indiana, this the 23rd day of December 1921.

HARRY W. NEAL.
